UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed April 26, 1924. Serial No. 709,109.

This invention relates to typewriting machines, with special reference to combined paper-feeding and column-stop locking devices for the carriages thereof.

5 In typewriting machines, particularly those of portable form, it is desirable that the number of operating parts be as few, light in weight and simple in structure, as is consistent with durability and strength.

10 It is thus advantageous to re-design and re-arrange certain parts that perform a single necessary function, wherever possible, so as to perform a double function, thus reducing the number of operating parts.

15 Ordinarily, a typewriting machine is provided with a paper-holding and paper-feeding bar or roller, extending the length of the platen, above the line of print and supported by the carriage ends, the bar being associated 20 with hangers, springs, raising means, etc., used in connection therewith, and for no other purpose.

It is also common to provide means for locking the column-stops, either individually 25 or grouped in operative relation on the stop-bar, such means usually consisting of a bar overhanging the entire range of stops, this bar also necessitating the use of spring-pressed mounting elements, and a manual controlling 30 device in maintaining the bar in operative or inoperative positions.

It is one of the objects of this invention to substitute a single structure for the several independent elements above mentioned, performing the functions of both, and operated 35 by a single manual motion.

Another purpose is to materially reduce the number of parts employed, and further, in the simplification of the same, tending to 40 economy in construction and weight reduction.

Other features and advantages will herein-after appear.

In the accompanying drawings,

45 Figure 1 is a transverse sectional view taken through the carriage and platen of a typewriting machine.

Figure 2 is a top plan view of the same, the central portion being broken away.

50 Figure 3 is an enlarged fragmentary detail view, showing the construction of the feed roller end pivot and its mounting.

Figure 4 is a similar view, in section, of roller and arm-end support.

The typewriting machine illustrated includes a carriage having end frame plate members 5 formed of pressed sheet-metal with inreaching flanged upper edges to afford a finished appearance and necessary stiffness.

5 A platen 6 is mounted on the platen shaft 7, journaled in the carriage ends 5 and provided on its extending end with a twirling knob by which the platen may be rotated in either direction.

65 A paper-guide 8 is pivotally mounted on the carriage base plate 9 and supports a feed roller 10 at its front, held normally in peripheral contact with the platen by springs 11.

70 The base plate 9 is formed with parallel runways co-operative with similar stationary runways 12, anti-friction elements 13 being interposed to provide an easy running carriage, which so far as has been described is of standard construction.

75 Near the rear of the carriage is a rock-shaft 14 having one end reduced to pivot in the right-hand carriage-end 5, and the opposite end suited to receive an axial pivot screw 15 threaded into the left-hand carriage-end.

80 On both ends of the rock-shaft 14, adjacent the carriage ends, are rigidly secured arms 16 provided with lateral outstanding hubs held to the shaft by pins 17, said arms and shaft forming a frame, swingable within the carriage.

85 The forwardly-extending ends 18 of these arms are bent at right angles towards each other and in these bent portions are screw-threaded openings receptive of the shanks 90 19 of knurled knobs 20 disposed at the upper front corners of the machine, convenient to an operator.

95 The straight portions of the arms 16, adjacent their bent ends, are formed with openings suited to receive stepped bushings 22 permanently riveted therein, these bushings revolvably receiving the pintles 23 of a feed roller 24, extending longitudinally of the platen and connecting the arms 16, in which 100 they are held by the stems 21 of the knobs 20, these stems entering annular grooves 25 in the feed roller 24.

To provide an effective biting surface on

the feed roller, it may be made of a rustless metal and slightly roughened, as by drawing, filing, and the surface may be broken up into sections by shallow grooves as shown at 5 26 in Figure 3.

The rear ends of the arms 16 have set in them fixed studs 27 parallel with the rock-shaft 14 and provided with heads, and on which are mounted rollers 28 projecting laterally outward below the flanged upper 10 edges of the carriage ends 5 by which they are partially obscured.

Co-operating with these rollers are flat springs 29 fixed to lugs 30 at the lower edge 15 of the carriage-ends by screws 31. The tension of the springs 29, pressing against the rollers 28, co-acts with the weight of the frame to force the feed-roller 24 into contact with the platen, but when the feed roller is 20 raised to the position shown by the broken lines in Figure 1, the springs bearing against the rollers 28, which, as indicated, have passed below the axis of the rock-shaft 14, will carry the arms 16 to a stop position against the 25 tie-rod 32.

A column-stop bar 33 is permanently secured to the carriage-ends 5 and provided with the usual form of rack teeth designed to receive between them a plurality of column- 30 stops 34.

To co-operate with these column-stops, which move with the platen, a carriage stop 35 is pivotally mounted, as at 36, to a stationary part of the machine, and may be 35 moved into the path of the column-stops 34 by a connection 37 to the tabulating key at the keyboard.

The rock-shaft 14 is flattened along one 40 side, as at 38, for a distance at least equal to the operative length of the stop-bar 33, and when the rock-shaft and feed roller 24 are in the position shown in full lines in Figure 1, it will be seen that it is impossible to remove the column-stops 34 from the stop-bar 33, due 45 to the interference of the rock-shaft 14, but when the rock-shaft, arms 16 and feed roller 24 are raised to the position shown by the broken lines in the same figure, the flat face 38 of the rock-shaft assumes a position parallel 50 and slightly spaced from the adjacent edges of the column-stops 34, permitting them to be readily removed from their support bar 38.

The feed roller 24 is an essential element in promoting proper feeding of a work-sheet 55 above the printing line, and were this roller used alone, it would still be necessary to support it on arms pivoted in some manner to the carriage-ends.

If the rock-shaft were employed merely to 60 lock the column-stops in operative position on their support bar, the rock-shaft would, likewise, have bearings in the carriage-ends, and means must be provided to rotate it into its two operative positions.

65 However, combining these two separate

functions as by locating the rock-shaft 14 in such position relative to the stops 34, as to interfere with their removal from the stop-bar 33, except when moved to a released position, dispenses with many parts that would 70 necessarily be employed were the rock-shaft and feed roller mounted for independent control, such arrangement being herein disclosed.

Variations may be resorted to within the 75 scope of the invention, and portions of the improvements may be used without others.

Having thus described my invention, I claim:

1. The combination with a typewriting machine carriage having a column-stop-bar and 80 a plurality of stops engageable thereon, of a rock-shaft pivoted between the carriage ends and having a flattened side permitting removal or engagement of said stops relative to the stop-bar when disposed in a plane parallel 85 thereto and locking the stops when in another position, and means for rotating said rock-shaft into either position.

2. The combination with a typewriting machine carriage having a column-stop-bar and 90 a plurality of stops engageable thereon, of a rock-shaft pivoted between the carriage ends, said rock-shaft being flattened along one side to allow adjustment of the stops on said 95 stop-bar when the flattened portion is parallel to their edges and locking the stops when said rock-shaft is in another position, means for rotating said rock-shaft into releasing or locking position, and means for maintaining the rock-shaft in either position automatically. 100

3. The combination with a typewriting machine carriage having a column-stop-bar and 105 a plurality of stops engageable thereon, of a rock-shaft pivoted between the carriage ends, said rock-shaft being flattened along one side to allow adjustment of the stops on said stop-bar when the flattened portion is parallel to 110 their edges and locking the stops when said rock-shaft is in another position, means for rotating said rock-shaft into locking or unlocking position, resilient means for maintaining the rock-shaft in either position, and a fixed stop locating the rock-shaft when in 115 unlocking position.

4. In a typewriting machine, the combination with a platen, a column-stop support and a plurality of stops adjustable therewith, of 120 releasable feed-roller-carrying means effective to lock said stops when the feed-roller is in position against the platen and to permit adjustment of said stops when the feed-roller is released from the platen.

5. The combination with a typewriting machine carriage having a column-stop-bar 125 and a plurality of stops engageable thereon, of a rock-shaft pivoted between the carriage ends, said rock-shaft being shaped in cross-section to release or retain said stops relative to the stop-bar in accordance with its pos- 130

tion, arms fixed on said rock-shaft, rollers pivoted on said arms, and springs on said carriage impinging on said rollers whereby said arms are maintained in either of two positions corresponding to the releasing or retaining positions of said rock-shaft.

6. In a typewriting machine, the combination with a platen, a column-stop support and a plurality of stops adjustable therealong, of 10 releasable feed-roller-carrying means effective to lock said stops when the feed-roller is in one position and to permit adjustment of said stops when the feed-roller is in another position.

15. 7. The combination with a typewriting machine carriage having a column-stop-bar and a plurality of stops engageable thereon, of a rock-shaft pivoted between the carriage ends, said rock-shaft being flattened along 20 one side to allow adjustment of the stops on said stop-bar when the flattened portion is parallel to their edges and locking the stops when said rock-shaft is in another position, means for rotating said rock-shaft into releasing or locking position, arms on said rock-shaft, rollers at the ends of said arms, the axis of said rollers being parallel with said rock-shaft, and resilient means pressing 25 against said rollers whereby their axes are yieldably maintained above or below the plane of the axis of said rock-shaft, said rock-shaft being held in its adjusted position thereby.

8. The combination with a typewriting machine carriage having a platen, a column-stop-bar and a plurality of stops removably engageable thereon, of a rock-shaft pivoted at its ends between the carriage ends, said rock-shaft having a flattened side coincident 30 with the operative length of said stop-bar adjacently parallel thereto, said flattened side permitting removal or attachment of the stops relative to the stop-bar when disposed in a plane parallel thereto and locking said stops when in another position, arms 35 rigidly fixed to said rock-shaft, a paper-feed-roller carried by the arms and normally positioned against the platen, and resilient elements on said carriage operative to maintain said arms in either raised or lowered position whereby 40 said rock-shaft locks or unlocks the stops on said stop-bar.

9. The combination with a typewriting machine carriage having a platen, a column-stop-bar and a plurality of stops removably engageable thereon, of a rock-shaft pivoted at its ends between the carriage ends, said rock-shaft having a flattened side coincident 45 with the operative length of said stop-bar adjacently parallel thereto, said flattened side permitting removal or attachment of the stops relative to the stop-bar when disposed in a plane parallel thereto and locking said stops when in another position, arms rigidly 50 fixed to said rock-shaft, said arms extending

to the front and rear of the carriage, resilient elements on said carriage co-operating with the rearward extensions of said arms to maintain said rock-shaft in either of two definite positions, and a paper-feed-roller carried between the forward extensions of said arms to impinge upon said platen. 70

10. The combination with a typewriting machine carriage having a platen, a column-stop-bar and a plurality of stops removably engageable thereon, of a rock-shaft pivoted at its ends between the carriage ends, said rock-shaft having a flattened side coincident with the operative length of said stop-bar adjacently parallel thereto, said flattened side 75 permitting removal or attachment of the stops relative to the stop-bar when disposed in a plane parallel thereto and locking said stops when in another position, arms fixed to said rock-shaft near the ends thereof to extend towards the front and rear of the carriage, a paper-feed-roller pivotally mounted in the forward ends of said arms, parallel with the axis of said platen, and means co-operative with the rear ends of said arms 80 normally forcing said roller into operative contact with said platen. 85

11. The combination with a typewriting machine carriage having a platen, a column-stop-bar and a plurality of stops removably engageable thereon, of a rock-shaft pivoted at its ends between the carriage ends, said rock-shaft having a flattened side coincident 90 with the operative length of said stop-bar adjacently parallel thereto, said flattened side permitting removal or attachment of the stops relative to the stop-bar when disposed in a plane parallel thereto and locking said stops when in another position, arms fixed to said rock-shaft near the ends thereof 95 to extend towards the front and rear of the carriage, a paper-feed-roller pivotally mounted in the forward ends of said arms parallel with the axis of said platen, means for releasing said roller, said releasing means 100 also being operative in manually raising said arms, resilient means for normally pressing said roller into engagement with said platen, said resilient means also yieldably retaining said arms when in raised position, and a stop for limiting the upward 105 movement of said arms. 110

12. The combination with a typewriting machine carriage having a platen, a column-stop-bar and a plurality of stops removably engageable thereon, of a rock-shaft pivoted at its ends between the carriage ends, said rock-shaft having a flattened side coincident with the operative length of said stop-bar adjacently parallel thereto, said flattened side 120 permitting removal or attachment of the stops relative to the stop-bar when disposed in a plane parallel thereto and locking said stops when in another position, arms fixed to said rock-shaft near the ends 125 130

thereof to extend towards the front and rear of the carriage, a paper-feed-roller pivotally mounted in the forward ends of said arms, mounted in the forward ends of said arms, said roller having annular recesses adjacent 5 its ends, detents carried by said arms removably engaging in the recesses, said detents having extending manually operable knobs, a stop fixed in said carriage limiting the upward movement of said arms, and resilient means for holding said arms in either of 10 their extreme positions.

13. The combination with a typewriting machine carriage having a platen, of a rock-shaft journaled in the carriage ends, arms 15 fixed on said rock-shaft extending to the front and rear of the carriage, said arms having inreaching forward ends, a paper-feed-roller having pintles journaled in the forward portions of said arms and being in normal contact with said platen, said roller having 20 annular recesses near its ends and presenting a broken surface, handle-knobs removably engaged in the inreaching ends of said arms, said knobs having stems engageable in the mentioned annular recesses, rollers pivoted on the rear ends of said arms, and spring elements fixed on said carriage 25 exerting pressure on said rollers normally stressing said arms and causing tensional engagement of said feed-roller with said platen.

14. In a typewriting machine, the combination with a column-stop-rock-bar and a plurality of stops removably adjustable 30 therealong, of releasable feed-roller-carrying means including a rock-shaft extending parallel with and adjacent the stops, said rock-shaft being shaped in cross-section to block the stops against removal when the feed-roller is in one position and to permit 35 removal of the stops when said feed-roller is in another position.

15. In a typewriting machine, the combination with a platen, of a paper-feed-roller, 40 arms for swinging the roller toward or away 45 from the platen, the free ends of said arms

including journals for the roller, the latter having annular recesses adjacent the journals, and finger-pieces carried by said arms, said finger-pieces including detents removably engaging the recesses to hold the roller 50 within the journals.

16. In a typewriting machine, the combination with a carriage having a platen, a column-stop-bar and a series of column-stops 55 loosely set therealong, of a feed-roller to bear against the surface of the platen, a frame carried by the carriage to support the feed-roller in engagement with the platen, and means mounted on said frame to prevent the 60 removal of the column-stops from the column-stop-bar.

17. In a typewriting machine, the combination with a carriage having a platen, a column-stop-bar and a series of column-stops 65 loosely set therealong, of a feed-roller to bear against the surface of the platen, and a frame movable within the carriage and operable at one position thereof to support the feed-roller against the platen and having means 70 mounted thereon to prevent displacement of the column-stops when in such position and operable at another position thereof to provide for the release of the feed-roller from the platen and arrange said means in a manner to permit the release of the column-stops 75 from the stop-bar.

18. In a typewriting machine, the combination with a carriage having a platen, a column-stop-bar and a series of column-stops 80 loosely set therealong, of a frame supported by said carriage, a feed-roller rotatably mounted at the forward end of said frame, said frame being movable to cause engagement of said roller with said platen or separation therefrom, and locking means associated with said frame and movable upon movement of the latter to lock the stops on 85 said bar when the roller is moved to operative position and to release said stops when the roller is moved to inoperative position. 90

ALFRED G. F. KUROWSKI.
